DESIGN FOR A FOOD RECEPTACLE UNIT OR SIMILAR ARTICLE

Pauline R. Cutler, Murray Hill, N. J.

Application July 5, 1935, Serial No. 57,535

Term of patent 3½ years

To all whom it may concern:

Be it known that I, Pauline R. Cutler, a citizen of the United States of America and a resident of Murray Hill, in the county of Union and State of New Jersey, have invented a new, original, and ornamental Design for a Food Receptacle Unit or Similar Article, of which the following is a specification, reference being had to the accompanying drawing, forming part thereof.

In the drawings:

Fig. 1 is a perspective view of the food receptacle unit, showing my design;
Fig. 2 is a top plan view; and
Fig. 3 is a front elevational view.

I claim:

The ornamental design for a food receptacle unit or similar article as shown.

PAULINE R. CUTLER.
